UNITED STATES PATENT OFFICE.

CARL WINKLER, OF BERNE, SWITZERLAND.

CRUCIBLE USED FOR TYPOGRAPHIC PURPOSES.

1,244,935.

Specification of Letters Patent. Patented Oct. 30, 1917.

Application filed March 13, 1917. Serial No. 154,559.

To all whom it may concern:

Be it known that I, CARL WINKLER, a citizen of the Swiss Republic, residing at Berne, in Switzerland, have invented new and useful Improvements in Crucibles Used for Typographic Purposes, of which the following is a specification.

My invention relates to a crucible used for typographic purposes, particularly for casting stereotype plates and type metal blocks.

According to my invention a cock plug for regulating the outflow of the metal projects in the crucible itself to such an extent that the appendix, feeding head or riser formed in the outlet opening of the plug, by turning said plug, is separated from the plate, or the like, and brought back immediately into the crucible. For this purpose the cock-plug is preferably arranged in the bottom 20 of the crucible, and, indeed, in a recumbent, that is, in a horizontal or inclined position, because then the outlet opening can be so dimensioned that the mold is instantaneously filled, and the best conditions are obtained for the solidifying process for producing plates of homogeneous quality.

Further it has been found to be of great advantage to render the cock plug tight in its casing by lubricating the same with oil or other suitable lubricant, so that the thin molten metal cannot penetrate between the cock-plug and casing. This feature is of great importance in practice, because, without the lubricant, the plug, when sufficiently tightened to prevent the metal from flowing out, cannot be turned.

In the drawing representing the invention by way of example, Figure 1 shows a cross section of the cock-plug, Fig. 2, a longitudinal section on the line A—B in Fig. 1, and Fig. 3, a longitudinal section on C—D in Fig. 1, in which however the lubricant is distributed in a different way to that shown in Figs. 1 and 2.

45 *a* is the horizontal, or approximately horizontal, cock-plug, which is arranged to turn in the wall *b* of the crucible, and thus to open and close the opening *c* forming part of the mold *d*. The cock-plug is cut away at *e* to form an outlet opening for the molten metal. In the angular position of the cock-plug shown in Fig. 1 the molten metal in the crucible can flow freely into the mold *d*, said opening having, in this case, the same 50 length (Fig. 2) as the mold. The metal in the opening *e* forms, or exercises the func-

tion of the feeding head of so great importance for obtaining a casting of good quality throughout, and this feeding head is cut off and returned to the crucible by simply turning the cock-plug *a* through a small angle in the direction of the hands of a clock (Fig. 1).

For the purpose of rendering this plug sufficiently tight for preventing the molten metal from flowing out a bore *f* (Figs. 1 and 2) is provided in the same to which a lubricant, such as oil, is fed at *g* and this lubricant passes through the channels *h* to the circumference of the plug, which is thus lubricated.

In the construction shown in Fig. 3 there is no bore in the cock-plug itself, but a channel *i* is provided in the casing of said plug, that is, in the wall *b* of the crucible. 75 This common channel is connected by channels *k* with the circumference of the plug. The lubricant is fed to the channel *i* through the opening *l*.

What I claim and desire to secure by Letters Patent of the United States is:—

1. The combination with a crucible for typographic purposes, of a mold contiguous to said crucible, a cock-plug mounted in the wall of the crucible and having a cut-away portion arranged to face the interior of the crucible, and to constitute a portion thereof, said cock-plug being movable to bring the cut-away portion into position to effect communication between the interior of the crucible and the mold.

2. The combination with a crucible for typographic purposes, of a mold contiguous to said crucible, a cock-plug having a cut-away portion, said cut-away portion facing the interior of the crucible and forming a part thereof in one position of the cock-plug, said plug being rotatable on the central axis to bring the cut-away portion in position to effect communication between the interior of the crucible and the mold.

3. The combination with a crucible for typographic purposes, of a mold contiguous to said crucible, a cock-plug having a cut-away portion, said cut-away portion facing the interior of the crucible and forming a part thereof in one position of the cock-plug, said plug being rotatable on its central axis to bring the cut-away portion in position to effect communication between the interior of the crucible and the mold, and means for simultaneously preventing the en-

trance of the molten metal between the wall of the crucible and the surface of the cock-plug and for lubricating the cock-plug.

4. The combination with a crucible for typographic purposes, of a mold contiguous to said crucible, a cock-plug having a cut-away portion, said cut-away portion facing the interior of the crucible and forming a part thereof in one position of the cock-plug, 5 said plug being rotatable on its central axis to bring the cut-away portion in position to effect communication between the interior of the crucible and the mold, and means for simultaneously preventing the entrance of 10 the molten metal between the wall of the crucible and the surface of the cock-plug and for lubricating the cock-plug, said last named means comprising a film of lubricating oil disposed around the surface of the 15 cock-plug.
5. The combination with a crucible for typographic purposes, of a mold contiguous to said crucible, a cylindrical cock-plug hav- 20

ing a cut-away portion, said cut-away portion facing the interior of the crucible and 25 forming a part thereof in one position of the cock-plug, said plug being rotatable on its central axis to bring the cut-away portion in position to effect communication between the interior of the crucible and the 30 mold, and means for simultaneously preventing the entrance of the molten metal between the wall of the crucible and the surface of the cock-plug and for lubricating the cock-plug, said last named means comprising a film of lubricating oil disposed around the surface of the cock-plug, and 35 means for feeding the oil to the surface of the cock-plug in any position of the latter.

In testimony whereof I have signed my 40 name to this specification in the presence of the subscribing witness.

CARL WINKLER.

Witness:

O. NESENBACH.
